Primary Examiner — Lauren D McVey(74) *Attorney, Agent, or Firm* — MacMillan, Sobanski & Todd, LLC(57) **CLAIM**

The ornamental design for a model of a molecular bond, as shown and described.

DESCRIPTION

FIG. 1 is a perspective view of a model of a molecular bond showing my new design;

FIG. 2 is a front end view thereof, the rear end view being a mirror image thereof;

FIG. 3 is a left side view thereof, the right side view being a mirror image thereof;

FIG. 4 is a top view thereof; and,

FIG. 5 is a bottom view thereof.
